ATTORNEY

UNITED STATES PATENT OFFICE.

LOUIS CROSS, OF BROOKLYN, NEW YORK.

PLURALLY-FUSED SOCKET HEAD.

Application filed October 6, 1922. Serial No. 592,688.

To all whom it may concern:

Be it known that I, LOUIS CROSS, a citizen of the United States, and a resident of Brooklyn, in the county of Kings and State 5 of New York, have invented certain new and useful Improvements in Plurally-Fused Socket Heads, of which the following is a specification.

This invention relates to improvements in 10 electrical devices, and more particularly to what are commonly known in the art as multiple attachment plugs.

In the installation of electrical circuits it is customary to determine the number of 15 current consuming devices to be used in a single circuit so as to avoid undue waste by using an oversize wire and as a result when additional devices, i. e. those not entering into the calculations prior to installation, are connected into the line, a larger volume of current enters the line so that the wires become overheated causing fires and other damage.

With the constantly increasing use of such 25 appliances as previously mentioned, there is a like demand for more outlets with the result that multiple outlet plugs are finding a large volume of varied uses and as the current consuming devices are not fully 30 standardized as to the current required for operation, the necessity of effectually preventing the overloading of electrical circuits becomes apparent.

It is therefore the principal object of this 35 invention to provide means for connecting a plurality of devices such as smoothing irons, lamps, heating pads, water heaters, toasters, urns and the like to a single outlet and to provide an individual protective device in circuit with each individual outlet from the 40 plug so as to prevent overloading of the line and the damage consequent thereto.

Another purpose is in the provision of a 45 separate fuse for each socket, each fuse being interchangeable and removably engaged within the body of the adapter plug in such manner that should a short circuit or other mishap cause a "blow out", the same is confined to the particular socket carrying the defective plug and not transmitted to the main line or other sockets, the continued use of which is not interrupted.

A further aim is to produce a compact, 50 neat appearing structure, capable of extensive use and which is not readily liable to become deranged or damaged.

These and other like objects are attained by the novel construction, combination and arrangement of parts hereinafter described and shown in the accompanying drawing 60 forming a material part of this disclosure, and in which:—

Figure 1 is a partial side elevational, partial longitudinal sectional view showing the 65 interior of a plug made in accordance with the invention and indicating its application.

Figure 2 is an edge view of the plug.

Figure 3 is a bottom plan view of the same, 70 the sockets being shown as empty.

Figure 4 is a perspective view of a double conductor as used therein.

Figure 5 is a similar view of one of the 75 return conductors.

The complete appliance, as shown in the drawing, comprises a body 10 made of any suitable non-conducting or insulating material to present two or more faces 11 extending radially from a central projection 12 over which is fixed a screw-cap 13 suited 80 to engage a standard socket and constituting one of the conductor elements.

The protruding end 14 of the plug projection forms a seat for the center contact 15 its conductor 16 passing through an axial 85 opening in the head 10 to the recess 17.

Fixed in openings 18, extending radially in from the plug faces 11, are metal sleeves 19 threaded to receive ordinary commercial fuse plugs 20, the same being easily engaged 90 or removed by their knurled extending heads 21.

Adjacent the faces 11, the plug body is extended outwardly in register to provide bosses 22 having openings 23 containing 95 metal sockets 24 of standard type adapted to operatively receive the lamp plug 25 or one of similar nature as the plug 25' of an extension cord 26.

It may be noted that the several sockets 100 24 are not parallel, it being preferable to arrange them divergently for clearance and like purposes.

The inreaching flange at the bottom of the socket 24 is secured by screws to the body, 105 one of the screws 27 passing through the outturned foot 28 of a double conductor having angularly inclined elements 29 leading to parallel portions 30 connected at their opposite ends by a cross piece 31 containing a central opening 32.

As will be seen in Fig. 1, this conductor

is disposed in the space 17 of the plug body, its terminals leading to opposed sockets and its center element 31 engaged by the lower end of the conductor 16 which is riveted 5 after passing through the opening 32, thus, in connection with the screws 27, maintaining it in fixed position to convey current to the sockets 24 and whatever plug may be engaged therein.

10 The center contact of an attachment plug or lamp based when properly positioned engages a reversely bent spring contact 33 formed with an angular arm 34 integral with the conductor 35, the same passing 15 through a recess 36 formed in the body 10 between the bottoms of the recesses 18 and 23.

These conductors 35 are held in firm relation at the bottom of the recesses 18 by 20 screws 37 and have their opposite ends re-entrantly turned to provide terminals 38 for engaging the center contacts 39 of the fuse plugs 20.

Said fuse plugs are also in electrical 25 engagement along their metal casings with conductors 40 passing through openings 41 in the plug extension 12 and engaging the casing 13 previously described.

It will thus be seen that when the device 30 is threaded into a socket and one or more of the current consuming devices are connected in the sockets of the plug, the current will flow through the central contact 15 and thence through the conductor 16 and 35 double conductor to the center contacts 33.

Assuming that the lamp bulb is in position as illustrated, it will be seen that the current will flow through the threaded shell or socket 24 and lamp base 25, through the 40 center contact of the lamp to the contact 33.

Continuing, the current will enter the center contact 39 of the fuse plug 20 through the conductor 35 and passing through the fuse plug, out through the 45 threaded shell 19, will enter the shell 13 through conductors 40 and return to the outlet socket.

Obviously should a current consuming device of too high an amperage be connected

to the device, the fuse 20 will be blown out 50 and the line protected from overheating.

Although the foregoing is descriptive of the preferred embodiment of the invention, it will be apparent that minor changes may be made in its construction, without the exercise of invention or conflicting with the scope of the claims hereto appended.

Having thus described my invention, what I claim as new and desire to secure by Letters Patent, is:—

1. A multiple attachment plug comprising a chambered integral insulator having opposed lateral recesses in its body and sockets in its lower end, said sockets containing conducting linings, a conducting casing on 65 the upper attaching end of said plug, a fuse removably engaged in each recess said fuses having one pole in electrical engagement with said casing, a contact fixed in the attaching end of said plug, a conductor disposed in the chamber of said insulator, said conductor being engaged at its ends with the socket linings and at its center with said contact, and independent conductors in said body extending between said sockets and 70 recesses in electrical engagement with the other pole of said fuses.

2. A multiple attachment plug comprising a dielectric body having a conducting ferrule engageable in an outlet socket bipolar fuses removably engaged in lateral recesses in said body, one pole of each fuse being in electrical engagement with said ferrule, said body having divergent sockets in the end opposite said ferrule, conducting 85 linings in said sockets, a unitary conductor engaging each lining and extending into said body, a contact in said body central of said ferrule and insulated therefrom, said contact being fixedly engaged with said conductor, and conductors in said body having re-entrantly turned ends respectively engaging the other poles of said fuses and extending into said sockets.

In testimony whereof I have signed my 95 name to this application.

LOUIS CROSS.
